UNITED STATES PATENT OFFICE.

HENRY ASHTON RAMSAY, OF BALTIMORE, MARYLAND.

HYDRO-PNEUMATIC MECHANISM TO CHECK RECOIL OF GUNS IN HEAVY ORDNANCE.

SPECIFICATION forming part of Letters Patent No. 437,797, dated October 7, 1890.

Application filed January 23, 1890. Serial No. 337,909. (No model.)

To all whom it may concern:

Be it known that I, HENRY ASHTON RAMSAY, residing in the city of Baltimore, State of Maryland, have invented an Improved Gun Mounting, with a new and useful hydro-pneumatic mechanism for neutralizing the effect produced by the recoil of guns in heavy ordnance and for automatically returning a piece to battery after the recoil, of which the following is a specification.

My invention relates to improvements in the mounting of heavy ordnance, in which it is desired to check the recoil of guns and automatically return the piece to battery after its discharge; and the objects of my invention are, first, to provide a cushioning medium to neutralize the effect of the shock occasioned by the reaction of the piece at the time of firing; secondly, to automatically return the piece to the position it occupied before being discharged and without losing its sight ready to fire again; thirdly, to provide a device to properly govern the elevation and depression of a gun while permitting the piece to slide freely within its trunnion-band, the gun being suspended in a mounting fixed about a central or forward pivot, the mounting not partaking of the backward motion occasioned by the recoil of the piece, and by these means to so gradually arrest the recoil of the piece as not to bring an injurious shock on the mounting, to prevent the necessity of having the mounting in two parts with one of them movable. To enable me to arrange the cushioning-cylinders attached to the gun itself so that the bore of the gun will always be parallel with the central axis of the cylinders, causing the reactionary effect of the resisting medium in the cylinders to be opposite to the energy exerted by the recoil and equally effective at all angles of elevation, and to provide for the admission of the resisting fluid-pressure in the cylinders by introducing it through the trunnion of the piece, providing a conduit having connection with an accumulator. I attain these objects by the mechanism illustrated in the following drawings, in which—

Figure 1 is a plan view of the piece and mounting. Fig. 2 is a side elevation of the gun and mounting. Fig. 3 is a cross or trans-

verse section through the trunnions. Fig. 4 is a detail drawing of the elevating-sector and guide. Fig. 5 is an inverted view of part of the piece, looking upward, showing the recoil-cylinders in section cut through A B, Fig. 6. Fig. 6 is an end view of the trunnion-band, looking toward the breech of the gun. Fig. 7 is an enlarged view of part of the gun in side elevation, showing the recoil-cylinders, trunnion-band, piston-rod, and lugs, the side cheek of the mounting being removed.

The same letters indicate like parts throughout all the views.

The two recoil-cylinders shown in the several views and marked D and E are proportioned according to the caliber and maximum charges to be used in the piece, considered in connection with the pressure to be maintained in an accumulator and pressure-pump to be provided, but not shown in the drawings, as they are to be of any ordinary construction. These cylinders are rigidly secured to a reinforcing band M, shrunk on or otherwise secured to the barrel of the gun. The piston in D is secured to the solid piston-rod shown rigidly secured to a lug provided on the trunnion-band. A hollow plunger-rod F is also secured to a lug on the trunnion-band L. This rod enters the cylinder E.

Embracing and freely moving on the rod F, independent of the latter's motion, a piston H is provided with wing-guides, as shown.

A non-return valve K is provided on the outboard head of cylinder E, regulating the opening in a pipe connecting it with D; also a non-return valve N and chamber on the outboard of D, communicating with the atmosphere.

Communication between the cylinders D and E is provided for by the regulating-valve P.

A conduit is provided by the pipe R to admit air under pressure through the trunnion and the plunger-rod F to the cylinder E.

Now the operation of the mounting with its recoil-cylinders and maneuvering apparatus is as follows: It being understood that the trunnion-band, while embracing the barrel of the gun, permits the latter to have an independent reciprocal motion, and the cylinder-band is shrunk on or otherwise secured to the

100

barrel of the gun, and hence must move with it, carrying the cylinders. Suppose the gun to be run out into battery with the piston close to the rear cylinder-head. The cylinder D is 5 filled with oil, water, glycerine, or other fluid. The loose piston in E is forced to the inboard end of its stroke by admitting air under pressure through the hollow plunger-rod F, communicating through the hollow trunnion 10 to the accumulator. Now, when the piece is fired the effect will be to recoil, carrying the cylinders rearward, the piston and plunger rods being stationary. The fluid in D flows through P into E, further compressing the 15 air in E, thus gradually retarding the rearward movement of the gun until the energy occasioned by the firing of the piece has been absorbed or neutralized. The expansion of the compressed air in E will now react, force 20 the liquid back into D, thus returning the piece to battery and restoring the equilibrium.

Shock to the mounting from the possible effect of counter-recoil is taken up or neutralized by the cushioning air in the rear end of cylinder D, drawn through the non-return valve N at the time of the gun's recoil, and the possibility of dangerous pressure on the recoil-cylinder head D from the cushioning-air being too great, so as not to permit the gun's going into battery, is prevented by a communicating pipe and valve K, the latter opening, if necessary, and equalizing the pressure in the two cylinders. These valves 35 have detached stems, so they act automatically; but the stems and hand-wheels regulate the amount of opening.

Should it be desired to run the gun in without firing for any reason, it will only be necessary to open the non-return valve on E, when the air under pressure in E will pass 40 into D and force the cylinder rearward, bringing the gun with it, the valve N being closed and a small valve used to introduce 45 the liquid in the first place into D, slightly opened to start the movement, if necessary.

A small accumulator and hand-pump are provided to compress the air, and a conduit is arranged to carry the compressed air from 50 the compressor to the hollow trunnion, through which it passes into the channel provided in the trunnion band and lug, through the hollow piston-rod, to the cylinder E. As the effect of the recoil of the piece is to compress 55 the air, when the air is once compressed in the accumulator to the desired pressure, which can be done by a few strokes of a small air-pump, the volume of the clear space in the cylinder being small, it will require the 60 expenditure of little or no power to maintain the desired pressure in the accumulator.

The gun is elevated and depressed by a worm-wheel segment or sector. (Shown at O in Figs. 2 and 3 and as a separate detail in Fig. 65 4.) This segment is bored at the eye to fit around the trunnion, oscillating freely around

the trunnion as a center with an independent motion. At Y, forming part of the sector, there is a guide to receive the supplemental trunnion S, thus providing a guide for this 70 trunnion, which permits reciprocating while preventing twisting motion to the piece, (the latter caused by the reactionary effect from the discharge of rifled projectiles,) and at the same time providing a means of governing its 75 elevation and depression to an extreme and unusual degree. The periphery of the segment is provided with helical teeth, into which the threads or teeth of a worm-wheel engage, this worm-wheel pinion being keyed to a shaft 80 revolving in bearings secured to the cheek of the mounting and operated by a hand-wheel W. This device effectually controls the piece in its vertical movement with the greatest nicety and exactness with expenditure of lit- 85 tle power, as the combination of the screw and lever give a large translation of power to work.

In the case of light charges, small-calibered pieces, and consequently reduced inertia in 90 the recoil, the accumulator and pressure-pump will not be necessary, as the air drawn into cylinder E by a non-return valve in the rear head will afford sufficient cushion for the pistons, and in this case the pistons would be 95 fixed and loose on the rods, as before, but rod F would not be hollow.

The piece is trained horizontally about its central pivot by a pinion geared into a toothed rack secured to the periphery of the turn-table. The upright shaft, working in bearings 100 secured to the lower fixed part of the table, can be operated either by hand or power, as indicated in the drawings.

The central shaft is secured to the upper part 105 of the turn-table and turns in the lower part as a step-bearing. This shaft is hollow to admit air to the conduit, a pipe from the accumulator passing through the shaft and made tight by a proper gland and stuffing-box. 110

Friction between the faces of the two parts of the table is reduced by interposing anti-friction steel balls or double frustums of cones, as may be found best, as shown at V, while conical wheels support the turn-table at the 115 periphery, revolving on radial axles attached to and radiating from a central band U.

What I claim, and desire to secure by Letters Patent of the United States, is—

1. The combination, in a gun-mounting or mechanism for holding, controlling, and maneuvering guns, of recoil-cylinders secured rigidly to the barrel of a gun, placed in the front or rear of the trunnions, as may be most convenient, according to the preponderance of 120 the piece, said cylinders containing pistons or plungers, or both, moving freely within them, connected by solid and hollow piston- 125 rods to a trunnion-band embracing the barrel of the gun, but permitting its free reciprocating motion, in conjunction with the conduit admitting air, gas, water, or other liquid 130

through the hollow trunnion and trunnion-band, entering the cylinder E through the plunger-rod F, substantially as described.

2. The combination, in a gun-mounting, of 5 a sector with a worm-thread on its periphery, an eye bored to embrace but unattached to the trunnion, and provided with an arm containing a guide governing the supplemental trunnion Y, in conjunction with the helix or 10 worm pinion X, turning in bearings fixed to the cheek of the mounting, for the purpose set forth.

3. The combination, in a gun-mounting, of 15 trunnion-band L, with attached fixed trunnions in which the piece is suspended permitting oscillatory motion of the gun by the trunnions on the band oscillating in the fixed bearings provided on the stationary cheeks of the mounting, thus permitting vertical 20 movement, elevation, and depression of the barrel, while permitting free, independent, and unrestricted reciprocating motion of the

piece, in conjunction with the worm and sector, guide, and supplemental trunnion governing the elevation and depression of the 25 piece, all as set forth and described.

4. The combination of a hollow piston or 30 plunger rod with a hollow trunnion forming air or liquid conduit to cylinder E, in conjunction with the loose piston H, solid piston R, and regulating-valves P, K, and N, with cylinders D and E, rigidly secured to a reinforcing ring or band secured rigidly to the barrel of a gun and partaking of all its movements, together with the independent trunnion-band L and governing-sector O, regulating the elevation of the piece, in combination with the radiating turn-table about a fixed center, all as hereinbefore described, and for the purpose set forth.
